C. H. YOUNG

BRICK PALLET

Filed Feb. 10, 1921

Inventor:
Clarence H. Young,
by Emory Booth Janney & Varney,
Atty's

UNITED STATES PATENT OFFICE.

CLARENCE H. YOUNG, OF BOSTON, MASSACHUSETTS.

BRICK PALLET.

Application filed February 10, 1921. Serial No. 443,986.

To all whom it may concern:

Be it known that I, CLARENCE H. YOUNG, a citizen of the United States, and a resident of Boston, in the county of Suffolk and State 5 of Massachusetts, have invented an Improvement in Brick Pallets, of which the following description, in connection with the accompanying drawings, is a specification; like characters on the drawings representing like 10 parts.

This invention pertains to improvements in pallets, and more particularly, though not exclusively, to improvements in brick pallets. It is among the objects of the 15 invention to provide a brick pallet of simple construction, great strength and durability, while relatively light in weight, and which is very convenient for manipulation.

In the drawings, which show a preferred 20 form of one embodiment of my invention:—

Figure 1 is a bottom view of a brick pallet;

Fig. 2 is a section on the line 2—2 of Fig. 1, being partly in elevation;

Fig. 3 is a section on the line 3—3 of Fig. 2, being partly in elevation; and

Fig. 4 is an enlarged partial section on the same line as Fig. 2, being partly in elevation, and illustrating in detail a preferred form of 30 constructing an end of the pallet.

Referring to the drawings and to the preferred form of my invention selected for illustrative purposes, I have shown a pallet having a body portion 8 preferably formed 35 of sheet metal and having lateral down-turned flanges 9, preferably terminating in reverse flanges 10 to increase the strength of the pallet longitudinally while minimizing the danger of injury from careless handling and providing a relatively smooth bearing surface on the bottom of the pallet. The plate 8 forming the body portion of the pallet is preferably flanged downwardly and inwardly at its ends to provide smooth end 40 portions 11 and underlying flanges 12 reinforcing the plate adjacent its ends. The side flanges 9 preferably terminate at 13 somewhat short of the ends of the pallet, so that the ends of the pallet provide overhanging

portions which may be conveniently grasped 50 and which may conveniently fit over suitable supports. The pallet may be provided with transverse reinforcements 20, which may be formed as a part of a bent plate having a part 21 extending between the body plate 8 55 and its end flange 12 to reinforce and strengthen the end of the pallet, the part 21 preferably extending to a point adjacent the ends 11 of the pallet. The reinforcements 20 may be provided with any suitable at- 60 taching means typified by the flanged portions 22 at each end thereof lying against the reverse flanges 10 and adapted to be secured thereto and to the side flanges 9 of the pallet by any suitable securing means typi- 65 fied by the rivets 23.

The reinforcing means 20 preferably ex- 70 tends slightly below the bottom of the down-turned flanges at the sides of the pallet.

While I have shown and described a pre- 70 ferred form of pallet, it will be understood that considerable changes from the construction illustrated and described may be made without departing from the scope of my invention, which is best defined in the follow- 75 ing claims.

Claims:

1. A pallet having a sheet metal body portion, lateral flanges and reinforcing means 20 at points removed from the ends 80 of the pallet and extending between said lateral flanges, said reinforcing means being provided with extensions 21 extending toward the ends of the pallet, said sheet metal body portion being reversely flanged at its 85 ends to provide a part 12 turned over and underlying said extensions 21.

2. A pallet comprising, in combination, a body portion, lateral flanges thereon, a reinforcing piece between said lateral flanges, 90 projections from said reinforcing piece se- 95 cured to said lateral flanges and an extension from said reinforcing piece underlying said body portion toward the end of the pallet.

In testimony whereof, I have signed my 95 name to this specification.

CLARENCE H. YOUNG.
